UNITED STATES PATENT OFFICE

2,377,710

LIQUID ACTUATED CONTROLLING DEVICE

James A. Morgan, Houston, Tex.

Application July 17, 1944, Serial No. 545,359

1 Claim. (Cl. 137—68)

This invention relates to a liquid actuated controlling device.

An object of the invention is to provide a device of the character described which has been specially designed for use in automatically relieving the liquid from the tank of a scrubber or separator wherein entrained liquids and solids are separated from the gas or vapor.

The separator above referred to may be used for various purposes but is primarily designed for treating natural gas as it comes from the well so as to remove the oil, gas, other petroleum products and solids therefrom; and the invention herein described has been designed for the purpose of automatically relieving the liquids collected in the tank from the tank.

With the above and other objects in view the invention has particular relation to certain features of construction, arrangement of parts and use, an example of which is given in this specification and illustrated in the accompanying drawing wherein—

Figure 1 shows a side view of the separator, partly in section.

Figure 2 shows an enlarged fragmentary sectional view thereof showing the liquid actuated controlling device, partly in section; and

Figure 3 shows a cross sectional view taken on the line 3—3 of Figure 2.

Referring now more particularly to the drawing wherein like numerals of reference designate similar parts in each of the figures, the numeral 1 designates an upright shell or tank which may be of any conventional form and which may be supported on any suitable type of base as 2.

The tank has one or more inlet lines 3, two being shown. It also has an outlet line 4, said inlet and outlet line being valve controlled in the usual way. The shell is also equipped with a drain outlet 5 which extends into the tank and whose inner end is upturned.

The interior construction of the separator may be varied but as illustrated it is substantially the same as that disclosed in Patent No. 2,197,189 for Scrubber issued to applicant by the United States Patent Office on April 16, 1940.

Screwed onto the upturned end of the outlet line 5 there is a head 6 having a passageway 7 therethrough which is aligned with the passageway through the outlet line and whose upper end may be flared.

Upstanding from the head 6 there are the posts 8, 8 mounted on which are the upper and lower plates 9, 10, the former of which is slidably mounted on the posts and the latter of which is fixed thereto, as by welding.

The numeral 10 designates a float fixed to, and

depending from, which there is a spud 11 which extends through the upper plate 9 and is welded thereto.

The upper ends of the posts 8 are threaded and screwed thereon are the nuts 12 forming adjustable stops. These stops may be screwed up or down to vary the range of movement of the float 10.

Depending from the spud 11, and fixed thereto, there is a stem 13 whose lower end is pointed to conform to the contour of and to fit the flared upper end of the passageway 7 so as to close the same.

Fastened to the under side of the plate 10, on opposite sides, are the flat springs 14, 14 whose inner ends are curved to grip the stem when it is in its lower position. The weight of the float, spud and stem is sufficient to lower the stem between said springs to close the passageway 7 and to hold the stem in this closing position.

The liquid separated will gradually collect in the tank 1 and the buoyancy of the float will eventually cause the float to move upwardly, releasing the stem from said springs to open the passageway 7 and permit the liquid to drain out until the float has lowered a sufficient distance to close the passageway 7 whereupon the springs 14 will grip the stem and hold it closed until another load of liquid has accumulated. The springs 14 will hold the float against upward movement until a full load of liquid has accumulated whereupon the passageway 7 will be quickly opened.

The plate 10 has a central opening through which the stem 13 works snugly thus forming a guide for the stem.

The drawing and description are illustrative merely while the broad principle of the invention will be defined by the appended claim.

40. What I claim is:

In a separator having a liquid receiving tank provided with a drain outlet line whose inner end, within the tank, is upturned, a head on said outlet line provided with a passageway aligned with the passageway through the outlet line, posts upstanding from the head, a transverse lower plate fixed to said posts and having a guide opening, a transverse upper plate movable vertically on said posts, a float fixed to said upper plate, a stem depending from the float through the said guide opening and whose lower end is formed to close the passageway through the head and friction members on the lower plate arranged to frictionally engage the stem to hold it temporarily in lower position to maintain the passageway closed.

JAMES A. MORGAN.
